ANIMATED SIGN

Harry R. Van Deventer and John J. Shively, New York, N. Y., assignors, by mesne assignments, to Service Devices, Incorporated, New York, N. Y., a corporation of New York

Application September 6, 1935, Serial No. 39,360

2 Claims. (Cl. 40—53)

This invention relates to improvements in animated signs.

An object of the invention is to provide a display sign in which a succession of images may be automatically presented to view.

Another object is to provide a sign of the above type in which the successive images are disposed on a strip of film or the like.

A further object is to provide means by which the images may be illuminated from the rear.

A still further object is to provide a structure comprising luminous gaseous tubes, such as neon tubes, and suitable reflecting system so disposed that images or symbols on the film may appear as successive luminous tube signs.

Another purpose is to provide means by which the film may be moved steadily to display a continuous advertising message or the like disposed throughout its entire length.

Another object is to provide suitable means by which the film may be automatically rewound and restarted on its active cycle, by which a suitable dwell is provided during the display of each individual image, and by which the light is extinguished while changing images and during rewinding.

Other objects and advantages will appear during the course of the following description in connection with the accompanying drawings in which:

Figure 1 is a perspective view of the device with the exterior partially broken away;

Figure 2 is a detail view of the driving motor, clutches and gearings; and

Figure 3 is a diagrammatic layout of the mechanical elements and electrical circuits.

Referring to Figure 1, a base 10, which may be of insulating material, has mounted thereon a removable casing 11, and an internal frame 12 shown broken away to disclose the parts behind it. The outer casing 11 has an aperture 13 provided with a transparent closure 14 of glass or the like. An upper roller 15 and a lower roller 16 are mounted respectively on shafts 17 and 18 journaled in the frame 12. The rollers 15 and 16 carry grooved pulleys 19 and 20 connected by belts 21 and 22 to driving pulleys 24 and 23 which are journaled on shafts 26 and 25 and adapted to be coupled thereto by means of magnetic clutches 28 and 27.

A drive motor 29 carries on its shaft a pinion 30 meshing with a gear 31 on the shaft 25, while shaft 25 also carries a pinion 32 meshing with a gear 33 on shaft 26 as shown in Figure 2. It is evident that when the motor 29 is running the

shaft 25 is driven in one direction at reduced speed, while the shaft 26 is driven in the opposite direction at doubly reduced speed.

Mounted on the base 10 is a flasher 34 provided with a motor 35 adapted to drive through any suitable speed reducing means a shaft 34a carrying commutators 36, 37, and 38 as shown diagrammatically in Figure 3. The commutators 36, 37, and 38 are provided with slip rings 39, 40, and 41 connected to their peripheral conducting segments 42, 43, and 44 respectively. Contact brushes 45, 46, and 47 engage the slip rings in the order named, while brushes 48 and 49 are adapted to engage the segments 42 and 43 respectively. Two angularly spaced brushes 50 and 51 are provided to engage the segment 44 for reasons hereinafter explained.

The numeral 52 indicates a transformer connected by leads 90 to a luminous tube grid 53 provided with a suitable reflector 54, preferably of the split parabolic type described and claimed in application Serial No. 22,333. The grid 53 is clamped to a panel of glass or other transparent or translucent material 55 supported in rails 55a forming part of the frame 12. The panel 55 registers with the aperture 13 in the outer casing 11.

A strip film 56 of non-conducting transparent or translucent material is wound on the rollers 15 and 16, the extreme ends thereof being secured to the rollers by any suitable means such as a strip clamp or by acetone or other adhesive.

The film 56 has along one side a series of slots or perforations 57 spaced apart a distance substantially equal to the spacing of images 56a on the film 56. Brushes 58 and 59, mounted adjacent the rollers 15 and 16 but normally insulated therefrom, are adapted to engage the slots 57. A third brush 60, insulatedly mounted on the upper rail 55a, is also adapted to engage slots 57 so as to spring through them and make contact with a similarly mounted metal platen 61.

Brushes 58 and 59 are connected by means of leads 62 and 63 respectively to magnets 69 and 63 of a magnetic switch 97. The rollers 15 and 16 are of metal and may be connected to one feeder 73 of a current supply in any suitable manner such as by connecting 73 to the frame 12, but to clarify the diagram, Figure 3, leads 93 and 94 are shown connecting feeder 73 to brushes 93a and 94a making contact with the rollers.

In operation, assuming the film to be rewound on the lower roller 16 until only part of one wrap remains on the upper roller 15, the last notch 57 upon registering with the brush 58 allows the

latter to make contact with the roller 15. A circuit is thereby closed from feeder 67 through the magnet 69, lead 62, brush 58, roller 15, and lead 93 back to the feeder 73. The magnet 69 is energized and throws the switch arm 66 into contact with point 71, at the same time breaking the circuit to clutch 27 at point 72.

This closes a circuit from feeder 67 through the arm 66, point 71, leads 74 and 80, commutator 38, lead 85, switch 78 and lead 86 to the clutch 28, thence through lead 77 to the feeder 73. The motor 29, being directly connected across the feeders, continues to run and the clutch 28 engages. The pulley 24, belt 21 and pulley 19 now drive the roller 15 clockwise, moving the film upward.

As a picture or sign on the film comes into registry with the aperture 13 the brush 60 penetrates a slot 57 and makes contact with the platen 61. This closes a circuit through the lead 84, brush 60, platen 61, lead 83, switch 75, lead 82, magnet 79, lead 81, commutator 38, and lead 77 to the feeder 73. The magnet 79 is thereby energized throwing the switch 78 to the left, which performs the following functions:

The circuit is broken between leads 85 and 86, thus throwing out the clutch 28 and stopping the film.

A connection is established between leads 81 and 88, starting the flasher motor 35. The commutator 36 revolves counter-clockwise, brush 48 engaging segment 42 and thereby energizing the transformer 52 which illuminates the grid 53.

At the same time segment 44 on commutator 38 breaks contact with brush 51, de-energizing the magnet 19 and allowing switch 78 to throw to the right as shown. This closes the connection from 85 to 86, but as segment 44 has previously broken contact with brush 50 as described, the clutch 28 remains disengaged. The throw of switch 78 also opens the connection from 87 to 88, but the commutator 37 has meanwhile established a parallel connection through brush 49 so that the flasher motor 35 continues to run.

The sign now remains illuminated with the film stationary until the flasher shaft 34a and its commutators have made nearly a complete revolution, when segment 44 encounters brush 50, engaging clutch 28 as before and moving slot 51 out of registry with brush 60. At the same time commutator 36 breaks the transformer circuit. Finally segment 44 contacts brush 51 and commutator 37 breaks the circuit of the flasher motor 35, stopping the commutators in the position shown in Figure 3.

The film 56 continues to move upward until the next slot 57 allows the brush 60 again to contact platen 61, repeating the entire cycle as described.

When the film has wound upward until only the inner wrap remains on roller 16 the brush 59 penetrates the last slot 57 establishing a circuit through magnet 63 and throwing arm 66 clockwise. Arm 66 breaks contact with point 71, thus cutting off all current to the transformer, flashing mechanism and clutch 28, and engages point 72 to energize the clutch 27. The pulley 23, belt 22 and pulley 20 now drive the roller 16 counter-clockwise and rewinding the film upward until the last slot 57 on the upper end of the film registers with upper brush 58, when the entire operating cycle is repeated as described.

To summarize, the device automatically registers a succession of images in the sign, each image being illuminated and displayed for a length of time necessary for the flasher shaft to complete slightly less than one revolution. The sign is darkened while the images are changed, and when the entire series has been completed the film rewinds, the sign also being dark during rewinding.

In case it is desired to illuminate a continuous reading sign the switch 75 is thrown downward. This cuts the circuit to the platen 61, disabling the intermittent mechanism. At the same time a circuit is made around the commutator 36. The sign is now controlled entirely by the upper 10 and lower brushes 58 and 59 and the magnets 69 and 63. The film moves alternately down and up throughout its entire length, the grid being illuminated only during the upward motion. It is obvious that if desired the device may be constructed to allow the working or illuminated period to occur during downward movement and the rewind to be upward. Due to the gearing arrangement shown, the rewind occurs at higher speed than the working motion. 25

It will be noted that the upper and lower brushes can make contact with their respective rollers only when a single thickness of film is on the roller, as the second wrap interposes insulation. This prevents improper actuation of 30 clutches, since contacts can be made with the rollers only by the last slots 57 on the respective ends of the film 56. However, when the film is intended only for continuous wind and rewind operation as described, the slots 57 may be 35 omitted, the contact being made with the bare rollers as the fastened ends of the film run from under the brushes.

While the invention has been described in preferred form it is not limited to the precise structures shown, as various modifications may be made without departing from the scope of the appended claims. 40

What is claimed is:

1. In a display device in combination, a pair 45 of laterally spaced rollers having conducting surfaces, a film of insulating material spirally rollable on said rollers and having its opposite ends attached respectively thereto, said film having a perforation in its first lap on each of said rollers, 50 means to alternately drive said rollers whereby said film may be rolled back and forth between them, and electrical control means for said driving means including a brush adjacent each roller and adapted to make contact with the conducting face thereof through said perforation whereby a circuit may be established while retaining a portion of said film on said roller behind said brush, the second laps of said film on said rollers being adapted to override said perforations to 55 break said contacts.

2. In an electrical control device, switching means including a roller having a conducting surface, an insulating film spirally rollable thereon and having a perforation in its first lap, and 60 means to make contact with said surface through said perforation whereby a circuit may be established, the second lap of said film on said roller being adapted to override said perforation whereby said contact may be broken. 65
